UNITED STATES PATENT OFFICE.

ALFRED C. GILBERT, OF HAMDEN, CONNECTICUT, ASSIGNOR TO THE A. C. GILBERT COMPANY, OF NEW HAVEN, CONNECTICUT, A CORPORATION OF MARYLAND.

DESIGN FOR A TOY MACHINE FRAME.

Application filed May 10, 1928. Serial No. 26,624. Term of patent 14 years.

To all whom it may concern:

Be it known that I, ALFRED C. GILBERT, a citizen of the United States, residing in Hamden, in the county of New Haven and State of Connecticut, have invented a new, original, and ornamental Design for a Toy Machine Frame, of which the following is a specification when taken in connection with the accompanying drawing, in which—

Fig. 1 is a front elevation in perspective of a toy machine frame, showing my new design, and

Fig. 2 is a rear elevation in perspective of the same.

I claim:

The ornamental design for a toy machine frame substantially as shown.

ALFRED C. GILBERT.
